UNITED STATES PATENT OFFICE.

WALTER H. KNIGHT, OF NEW BRIGHTON, NEW YORK, ASSIGNOR TO THE COMPRESSED AIR POWER COMPANY, OF NEW YORK, N. Y.

FLUID-PRESSURE MOTOR.

SPECIFICATION forming part of Letters Patent No. 590,228, dated September 21, 1897.

Application filed June 24, 1896. Serial No. 596,771. (No model.)

To all whom it may concern:

Be it known that I, WALTER H. KNIGHT, a citizen of the United States, residing at New Brighton, in the county of Richmond and 5 State of New York, have invented certain new and useful Improvements in Fluid-Pressure Motors, of which the following is a specification.

My invention relates to means for automatically controlling the supply of fuel to the heater of a compressed-air motor in order that the quantity of fuel burned and the degree of heat generated will be in proper proportion to the amount of work being done.

15 In the particular form of mechanism which I have illustrated in the accompanying drawing by a diagrammatic view I have provided means for opening the throttle of the compressed-air reservoir and shifting the valve-controlling device (the reversing-link) simultaneously with the opening of the cock which controls the supply of oil to an oil-heater which is adapted to heat the compressed air on its way to the motor.

25 In the drawing, A is a compressed-air reservoir, and B is the throttle-valve.

C is the heater-coil, communicating with the reservoir A through pipe D and with the distributing-chest E of the engine-cylinder F 30 through the pipe G.

H is the oil-burner, supported beneath the heating-coil C, and H' is the oil-supply pipe leading from the oil-reservoir K.

L is a turning valve or cock in the oil-supply pipe H'.

M is the reversing-link of the engine, by means of which the engine can be run in either direction or stopped entirely.

N is the hand-lever, which controls the opening and closing of the throttle-valve B by means of the connecting-link N', and the shifting of the link M through lever O and links O' O' and bell-crank O², and the opening and closing of the oil-cock L through the connecting-rod P.

When the throttle B is closed and the link M is in central position, the oil-cock L is

nearly closed, shutting off the main supply of oil and allowing only a sufficient quantity of oil to pass to keep the burner lighted. 50 When the handle is shifted to open the throttle-valve and run the engine in either direction, the oil-valve L will be opened to increase the flame of the burner for heating the air which is supplied to the engine-cylinder. If 55 the speed of the engine is reduced, the supply of oil and heat of the heater will be proportionately reduced.

Though I have shown but one form of mechanism for automatically controlling the supply of oil to the burner in proportion to the amount of work being done by the motor, I would have it understood that I do not limit myself to this specific mechanism; neither do I limit myself to the particular form of 65 valve-controlling device—the reversing-link motion.

Having thus described my invention, what I claim, and desire to secure by Letters Patent, is—

1. The combination of a motor, suitable valve-controlling devices for the motor, a fluid-reservoir, a heater communicating with the reservoir and with the motor, a throttle-valve, a burner for the heater, and a hand-operated 75 device for simultaneously controlling the valve-controlling devices, the throttle-valve and supply of fuel to the burner of the heater, substantially as set forth.

2. The combination of a motor having suitable valve-controlling devices, a compressed-air reservoir having a throttle-valve, a heating-coil communicating with the reservoir and the motor, a burner supported beneath the heating-coil, a fuel-reservoir, a pipe leading 85 from the reservoir to the burner, a valve in said pipe, and a controlling-handle suitably connected with the motor-valve-controlling devices, the throttle and the fuel-valve, substantially as set forth.

WALTER H. KNIGHT.
